UNITED STATES PATENT OFFICE.

GEORGE A. JOHNSON, OF CHICAGO, ILLINOIS, ASSIGNEE TO WILLIAM H. MINER, OF CHICAGO, ILLINOIS.

DRAFT-RIGGING FOR RAILWAY-CARS.

1,136,013.

Specification of Letters Patent.

Patented Apr. 20, 1915.

Application filed April 11, 1914. Serial No. 831,146.

To all whom it may concern:

Be it known that I, GEORGE A. JOHNSON, a citizen of the United States, residing at Chicago, in the county of Cook and State of Illinois, have invented a certain new and useful Improvement in Draft-Rigging for Railway-Cars, of which the following is a full, clear, concise, and exact description, reference being had to the accompanying drawings, forming a part of this specification.

My invention relates to improvements in draft rigging for railway cars.

The object of my invention is to provide a draft rigging of simple construction and efficient operation.

In the drawings forming a part of this specification, Figure 1 is a side elevation, partly in central vertical longitudinal section, of a draft rigging embodying my invention. Fig. 2 is a horizontal section, partly in plan view, the section being taken on the line 2—2 of Fig. 1. Fig. 3 is a cross section taken on line 3—3 of Fig. 1. In Figs. 1, 2 and 3, the draft rigging is shown in normal position. Fig. 4 is a horizontal section, partly in plan view, showing the position of the parts when in full buff. Fig. 5 is a detail showing in perspective the forward end of one of the limbs of the draft yoke.

Referring to the drawings, the numerals 6—6 indicate draft members or parts of the car frame to which the draft rigging is applied. The stop members 7—7 are secured to the inner faces of the draft members, the said stop members being each provided with inwardly projecting portions forming the upper and lower front stop-shoulders 8—8, upper and lower rear stop-shoulders 9—9, upper and lower rear limiting stops 10—10, and upper and lower front limiting stops 11—11. The stop members are forwardly provided with upper and lower yoke stop-shoulders 12—12. A draft yoke 13 is mounted in horizontal position between the draft members, one limb 14 thereof being received between the upper and lower stop-shoulders in one casting, and the other limb 15 thereof being received between the upper and lower shoulders in the other stop casting. Each limb of the yoke is provided near its forward end with shoulders 16—16, which are preferably oppositely arranged, one on the upper edge and one on the lower edge of

the limb, the said shoulders 16 being adapted to engage against the yoke stop shoulders 12 on rearward movement of the draw-bar. At their forward ends, the limbs of the yoke are each provided with a transverse slot 17, 60 the said slots being alined with the transverse slot 18 through the draw-bar 35, the said slots being adapted for the passage of the coupler-key 19. The coupler-key is received at its ends in slots 20—20 in adjacent portions of the draft members 6, the said slots being longitudinally extended to permit forward and rearward movement of the key therein. The slots 17 through the limbs of the yoke are rearwardly extended to permit the rearward travel of the key 19 therein on rearward movement of the draw-bar. Front and rear followers 21 and 22, respectively, are mounted between the stop members, the said followers being provided with 75 in-turned lugs 23—23.

A compression resisting device 24 is mounted between the followers, the said compression resisting device being preferably of a spring type, and comprising upper and 80 lower sets of springs 25 and 26, respectively, mounted in vertical twin arrangement. Each set of springs preferably comprises an outer spring 27 and an inner spring 28 nested therein, the inner springs being seated at 85 their ends about the lugs 23 with which the followers are provided. A tie-plate 29, removably secured to the draft members, preferably by means of the bolts 30—30, is adapted to support the compression resisting parts 90 of the draft rigging in position between the draft members. In preferable construction, the draft yoke is rearwardly provided with a filler block 31 adapted to engage against the rear face of the rear follower 22. The 95 front follower 21 is provided in preferable construction with a forwardly extended portion 33 passing between the inwardly projecting portions 34—34 of the stop members, the said inwardly projecting portions forming the front stop-shoulders 8 and the yoke stop-shoulders 12. In normal position of the parts of the draft rigging and in buffing action, the draw-bar 35 engages at its rear end against the projecting member 33 of the 100 front follower 21. The draft yoke is of a suitable length to permit the simultaneous engagement of the rear follower 22 against the rear stop-shoulders 9 and the rear end of the yoke, preferably the filler-block 31.

thereon, and the engagement of the shoulders 16 of the draft yoke against the yoke stop-shoulders 12 with which the stop members are provided. Thus in buffing action of 5 the draft rigging, the rear follower is held against rearward movement not only by the rear stop-shoulders 9, but also by the yoke stop-shoulders 12 through the medium of the draft yoke, thus distributing buffing shocks 10 along the length of the stop castings and the adjacent length of the draft members.

On forward movement of the draw-bar, the yoke is drawn forwardly by the 15 coupler-key, the yoke giving the rear follower 22 forward movement and compressing the springs against the front follower 21, which is stopped against forward movement by the front stop-shoulders 8. On rearward movement of the draw-bar, the coupler-key 20 has free rearward movement in the slots 17 in the draft yoke and in the adjacent slots in the draft members, the draw-bar forcing the front follower rearwardly, compressing the springs against the rear follower, the 25 rear follower being held against rearward movement by the draft yoke through the engagement of its shoulder 16 against the yoke stop-shoulders 12 and also by the rear stop-shoulders 9.

30 On full compression of the parts of the

draft rigging in buffing action, as illustrated in Fig. 4 of the drawings, the front follower is in engagement against the front limiting stop-shoulders, the shoulders of the draft-yoke are in engagement against the yoke 35 stop-shoulders near the forward ends of the stop members, and the rear follower is in engagement against the rear stop-shoulders and the rear end of the yoke, thus distributing shocks in excess of the capacity of the 40 compression resisting members to three points in the length of each stop member.

I claim:—

In a draft rigging for railway cars, the combination with stop members having upper and lower front stop shoulders for a front follower and provided also with separate yoke stop shoulders located in front of the follower stop shoulders, of followers, shock absorbing mechanism intermediate the 50 followers, and a horizontal yoke slidably mounted between said front stop shoulders, said horizontal yoke having upwardly and downwardly extending shoulders near the front end thereof arranged to engage said 55 yoke stop shoulders in buffing.

GEORGE A. JOHNSON.
